UNITED STATES PATENT OFFICE

2,151,262

HEAT UTILIZING APPLIANCE FOR RANGES

Jacob J. Bradley, Quakertown, Pa.

Application December 7, 1937, Serial No. 178,583

1 Claim. (Cl. 126—365)

This invention appertains to new and useful improvements in heating attachments for ranges, the principal object being to provide an attachment for ranges whereby heat usually lost from the flue is conserved and utilized for heating or maintaining warm various articles of food.

Another important object of the invention is to provide a heating attachment for ranges which will be exceedingly practical for use in bakery 10 shops, boarding houses, and elsewhere where food in quantities must be cooked or heated.

These and various other important objects and advantages of the invention will become apparent to the reader of the following specification:

15 In the drawings:

Figure 1 represents a vertical sectional view through the apparatus and partly through a range.

Figure 2 is a side elevational view of the 20 appliance.

Figure 3 is a vertical sectional view taken substantially on line 3—3 of Figure 1.

Figure 4 is a horizontal sectional view taken substantially on the line 4—4 of Figure 3.

25 Referring to the drawings wherein like numerals designate like parts, it can be seen that numeral 5 generally refers to a range having the water back 6 and the passage ways 7 for the products of combustion. Numeral 8 denotes the usual flue 30 attaching neck with which the apparatus generally referred to by numeral 9 is attached.

This appliance consists of a tank 10 having the narrow, elongated chamber 11 therein from 35 which rises the stack 12. The bottom of the tank 10 within the confines of the chamber 11 is provided with the opening 13 for receiving the neck 8. The upper portion of the tank 10 at the outside thereof is provided with the water gauge 14. Tie members 15 bridge the side walls of the 40 tank 10 to prevent spreading thereof.

A pipe 16 extends from the tank 10 to a point of consumption while the pipe 17 extends from the bottom of the tank 10 to the water back 6. A

5 pipe 18 extends from the water back 6 and connects as at 19 to the upper portion of the tank 10. Obviously, by virtue of the described relation of parts, there is a circulation of water between the tank 10 and the water back 6, the tank 10 serving as a reservoir for an abundance of water for the water back. As can be seen in Figure 1, the flue pipe 20 is connected to the upper end of the stack 12.

At opposite sides of the tank 10 are cabinet 10 structures generally referred to by numerals 21 and 22.

Each of these cabinet structures includes a back wall 22 which is provided with hook-like lugs 23 at its upper end for engagement over the 15 upper edges of the tank 10 and the angle arm members 24 which reinforce the tank walls at these points.

Each of these cabinets 21 and 22 is provided with a plurality of shelves 25 which divide the 20 cabinet into a plurality of compartments 26 each provided with a closure 27 having a handle 28.

Obviously various food stuffs can be placed in these compartments and the closures closed for the purpose of heating or warming the same. 25

While the foregoing specification sets forth the invention in specific terms, it is to be understood that numerous changes in the shape, size and materials may be resorted to without departing from the spirit and scope of the invention 30 as claimed hereinafter.

Having described the invention what is claimed as new is:

In combination with the water back of a range, 35 a tank, said range being provided with a flue, said flue extending through the tank, and circulatory pipes extending from the tank to the water back, said tank being provided with an elongated narrow compartment therein provided with a stack, said compartment and stack being interposed in 40 the range flue.

JACOB J. BRADLEY.
